Primary Examiner — Austin Murphy(74) *Attorney, Agent, or Firm* — Christensen O'Connor Johnson Kindness PLLC(57) **CLAIM**

The ornamental design for a clip for coordinate input device, as shown and described.

DESCRIPTION

FIG. 1 is a top front right perspective view of a clip for coordinate input device according to a representative embodiment of my new design;

FIG. 2 is a bottom rear left perspective view of a clip shown in FIG. 1;

FIG. 3 is a front view of the clip shown in FIG. 1;

FIG. 4 is a rear view of the clip shown in FIG. 1;

FIG. 5 is a left side view of the clip shown in FIG. 1, wherein the right side view is a mirror image of the left side view;

FIG. 6 is a top view of the clip shown in FIG. 1;

FIG. 7 is a bottom view of the clip shown in FIG. 1; and,

FIG. 8 is a top front right perspective view of a clip shown in FIG. 1 wherein the clip is coupled to a coordinate input device.

The broken lines in the drawings show portions of the clip for coordinate input device that form no part of the claimed design. While the solid lines in the drawings form part of the claimed design, the solid lines also provide written description of prospective embodiments with aspects that are not claimed when one or more of the solid lines are amended to broken lines.
